UNITED STATES PATENT OFFICE.

FREDERICK HARTMANN, OF HOBOKEN, NEW JERSEY.

CUTTING-OFF TOOL.

1,249,080.

Specification of Letters Patent. Patented Dec. 4, 1917.

Application filed June 11, 1917. Serial No. 174,159.

To all whom it may concern:

Be it known that I, FREDERICK HARTMANN, a citizen of the United States, and a resident of Hoboken, in the county of Hudson and State of New Jersey, have invented a new and Improved Cutting-Off Tool, of which the following is a full, clear, and exact description.

My invention relates to cutting-off tools particularly adapted for use on lathes.

An object of the invention is to provide an efficient and inexpensive tool which will eliminate the danger of gripping during the process of cutting.

A further object of the invention is to provide a cutting-off tool formed of two relatively movable cutting parts which are adapted to be fed alternately.

A still further object of the invention is to provide a cutting-off tool the cutting members of which are detachable from the feeding means so that they can be easily replaced without much labor.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a top plan of a cutting-off tool embodying my invention;

Fig. 2 is a similar view, certain parts of the tool holder being broken out to show the details of construction;

Fig. 3 is a longitudinal section through the tool;

Fig. 4 is a cross section on line 4—4, Fig. 3; and

Fig. 5 is a perspective view of the cutters and means for connecting the cutters to the feeding screw.

Referring to the drawings, 6 is the holder or housing which has a longitudinal bore 7 of rectangular cross section open at the front end of the tool, which end is cut on the bias. The housing has also a cylindrical bore 8 extending through the entire length of the housing. The portion 8' of the bore 8 beyond the bore 7 is threaded to receive a screw 9. The inner end of the screw has a

cam groove 10 the pitch of which is not less than that of the thread of the screw 9. The other end of the screw receives a manipulating member 10', which is preferably in the shape of a wheel.

A pair of blades 11, when side by side, fit snugly into the bore 7 of the housing 6, that is, the cross section of the two blades is identical with the cross section of the bore 7. Each of the blades has an extension 12 entering the groove, the extensions of the two blades being opposite one another. The cam groove is of such character that while one of the blades is moved by the advancement of the screw 9 of the threaded portion 8' of the housing, the other remains immovable; in consequence, each blade cuts independently as the tool is advanced. Due to that fact there is no chance for the tool to be jammed, as the groove is always larger than one of the cutting blades and in consequence, there is no chance for the cutting tool to grip and force the member to be cut off out of center, as happens in such cases.

In view of the fact that the blades 11 are made of special tool steel, it is preferable to provide detachable sections 13 which have extensions 12 for engaging the cam groove, and also dove-tailed projections 14 or recesses 15 for engaging corresponding recesses or projecting respectively in the blades 11.

I claim:

1. A cutting-off tool of the class described comprising a pair of cutting blades side by side and means for moving said blades alternately.

2. A cutting-off tool of the class described comprising a pair of cutting blades each having a cutting end, pointing in the same direction and means for moving said blades so as to advance the blades one after the other.

3. In a cutting-off tool of the class described, a housing, a pair of cutter side by side movable in the housing, and means associated with the housing and engaging the cutters for moving the cutters alternately.

4. In a cutting-off tool of the class described, a housing, a pair of cutters slidably mounted therein, and a screw in the housing, said screw having a cam groove, said cutters having means for engaging the cam groove, said cam groove being so related to

the threads of the screw that the cutters are moved alternately when the screw is moved in the housing.

5. In a cutting-off tool of the class described, a housing, a member adapted to be moved in and out of the housing, a pair of cutters in said housing, and means connecting said cutters to the movable member so that the cutters are moved in alternation substantially as and for the purpose set forth.

6. In a cutting-off tool of the class described, a housing, a pair of cutting blades slidably mounted in the housing, a screw in the housing having a cam groove the pitch of which is not less than the pitch of the thread, extensions from the blades engaging the cam groove, and means for revolving the screw in the housing.

7. A cutting-off tool of the class described comprising a pair of cutting blades disposed

side by side and a screw, including means for engaging the two blades and moving the blades alternately when the screw is rotated.

8. A cutting-off tool of the class described comprising a pair of cutting blades disposed side by side and a screw having a cam groove, said blades having means for engaging the cam groove of the screw and whereby the said blades are moved alternately when the screw is rotated.

9. In a cutting-off tool of the class described, a housing, a screw revolvable in the housing and movable longitudinally of same, said screw having a cam groove, slides in the housing having means for engaging the cam groove of the screw whereby said slides may be moved one after another longitudinally of the housing, and cutting blades detachably associated with said slides.

FRED HARTMANN.
